CORPORATION OF PENNSYLVANIA.

CONTAINER FOR CORROSIVE LIQUIDS SUCH AS HYDROFLUORIC ACID.

Application filed November 27, 1926. Serial No. 151,052.

The invention relates to containers for corrosive liquids such as hydrofluoric acid, and more particularly to bottles from which the corrosive liquids may be dispensed, for instance, in laboratories, drug stores, and the like. The invention has for its object to provide a container in the form of a bottle made of wax and reinforced in a novel manner to maintain the body of the bottle in an upright position in temperatures tending to soften the wax. A further object of the invention is to provide a bottle of this description, the neck of which is constructed in a novel manner to provide one or more pouring channels in the bore thereof to direct the liquid, which does not wet the wax surface, in a definite stream. Other objects will appear from the description hereinafter and the features of novelty will be pointed out in the claims.

Reference is had to the accompanying drawings which illustrate an example of the invention without defining its limits and in which Fig. 1 is an exterior elevation of the novel bottle, Fig. 2 is a vertical section on the line 2—2 of Fig. 1, Fig. 3 is a plan view of the bottle, Fig. 4 is a horizontal section through the neck thereof on the line 4—4 of Fig. 1, and Fig. 5 is a horizontal section through the body of the bottle on the line 5—5 of Fig. 1.

As shown in the drawings, the bottle comprises a body 10 and a continuing neck 11, both of which are made of wax, the body 10 being shown of cylindrical form; it will be understood that this form may be changed if for any reason this should be desired. The body 10 is provided with a reinforcing means which, in the illustrated example, is shown in the form of a tube or cylinder 12 of paper or other suitable material possessing an inherent rigidity sufficient to maintain the body 10 in an upright position if the wax, of which the body is, may become soft from any cause. The tube or cylinder 12 or equivalent reinforcing means is in molded connection with the body and extends lengthwise thereof throughout substantially its entire length, as shown in Fig. 2. It will be noted from this illustration that all of the reinforcing cylinder is spaced from the inner surface of the container and protected, therefore, from the corrosive liquid. In the preferred form, the tube 12, which corresponds in shape to the form of the body 10, is in external molded connection with the body or, in other words, sur-

rounds the same as shown in Fig. 5; the 55 aforesaid tube or cylinder 12 thus comprises the external surface of the body 10 and accordingly may have advertising matter or other data produced directly upon its outer surface by printing or otherwise or by pasting 60 suitable labels upon such outer surface. In any case, an acid-proof coating 13, preferably comprising a coating of transparent paraffin, covers the tube or cylinder 12 so as to protect it against the destructive action of any corrosive liquid or acid which may spill or run down the side of the bottle.

As shown in Figs. 2 and 4, the neck 11 of the bottle which forms a continuation of the body 10 includes a bore 14, the exit end of 70 which is of polygonal cross-section to provide a plurality of pouring channels 15 extending lengthwise of the neck; preferably, the bore 14 is of rectangular cross-section so as to provide pouring channels 15 located in pairs at 75 diametrically opposite points. A suitable stopper 16 is provided to fit the bore 15 for the purpose of closing the bottle. To insure a tight fit for the stopper 16, which is preferably tapered, the bore may be flared 80 outward slightly at its exit end. As shown in the drawings, the stopper has the usual mushroom top which may be reversed and sealed over the exit end of the bore upon the 85 end face of the neck by means of a hot wire when the bottle is filled; the latter is thus effectively sealed during storage or shipment. When removal of the stopper is desired, a 90 similar hot wire may be utilized to break the connection between said stopper and the end face of the neck and to permit the stopper to be utilized in the regular way.

Any suitable method may be followed in manufacturing bottles of the indicated kind, the following method having been utilized 95 and found successful. The reinforcing means or specifically the tube or cylinder 12 is inserted into a brass or other conventional mold in which the bottle is to be molded so as virtually to constitute a lining for said mold. The wax is then poured into the mold to mold 100 the bottle in the customary manner and to produce the body 10 and continuing neck 11 and at the same time to embed the tube or cylinder 12 in the body 10 so as to externally 105 surround the same. At the proper time, the molded bottle with the tube or cylinder in molded connection therewith is removed from

the mold and is dipped in an acid-resistant material such as a fairly transparent paraffin solution to provide the protecting coating 13. It will, of course, be understood that if the advertising matter or other data is to be directly produced upon the external surface of the tube or cylinder 12, this will be done at a proper time and in a proper manner prior to the insertion of the tube or cylinder into the mold. If the advertising matter or other data is in the form of labels, these may be pasted or otherwise attached to the cylinder either prior to its insertion into the mold or subsequently to the molding of the bottle therein; in the latter case, the labels, of course, are secured in place prior to the dipping of the bottle into the paraffin solution or its equivalent.

The wax bottles for hydrofluoric acid and other corrosive liquids, when allowed to stand on a laboratory shelf during the summer months or in surroundings where the temperature is artificially raised, frequently become softened to the point where they sag and bend over and thus spill the contents. With the aforesaid reinforcing means incorporated in the body of the bottle, particularly when this reinforcing means is in the form of a tube or cylinder, the bodies of the bottles are maintained in an upright position in the temperatures referred to and the aforesaid sagging or bending over is entirely prevented. In bottles of the indicated type, considerable difficulty has been experienced in directing the flow of liquid from the neck of the bottle, which constitutes a decided disadvantage because of the injurious and harmful characteristics of the corrosive liquids, such as hydrofluoric acid. With the present arrangement, this difficulty and these disadvantages are overcome by providing the pouring channels 15, which not only make it possible positively to direct and control the flow of the liquid, but make it possible also to pour out the contents in the form of drops, if this should be desired.

It will be understood that the term "wax" as used in the description, is intended to cover

ceresine and other waxes or any material which may comprise an equivalent thereof, and which tends to soften or otherwise lose its inherent rigidity in normally high temperatures.

The term "relatively" as employed in the claims in connection with the angularity of the pouring channels is to be understood to mean that the sharpness of the angular channel within the neck of the bottle is to be determined by the character of the liquid which the bottle is to contain and will be governed by the surface tension and viscosity of such liquid and the readiness with which or the extent to which the latter wets the inner wax surface of the neck of the bottle.

Various changes in the specific forms shown and described may be made within the scope of the claims without departing from the spirit of the invention.

We claim:

1. A bottle for containing acids and the like comprising a cylindrical body and a neck of wax, and a relatively rigid and heat resisting reinforcing cylinder inset in said body and in molded connection with, and spaced from the inner surface of, said body for maintaining the latter in an upright position at temperatures at which the wax tends to soften.

2. A bottle for containing acids and the like comprising a body and neck of wax, the neck having a bore, the exit end of which is so shaped as to provide a relatively sharp angular channel for directing the flow of liquid from said bottle.

3. A bottle for containing acids and the like comprising a body and neck of wax, the neck having a bore, the exit end of which is of rectangular cross-section to provide relatively sharp angular pouring channels located in pairs at diametrically opposite points for directing the flow of liquid from said bottle.

In testimony whereof we have hereunto set our hands.

ARTHUR W. WILKINSON.
CLARENCE W. RIEGEL.
